UNITED STATES PATENT OFFICE.

LOUISE A. PITTS, OF OAKLAND, CALIFORNIA.

DESIGN FOR A CAKE-TURNER.

SPECIFICATION forming part of Design No. 29,621, dated November 8, 1898.

Application filed August 17, 1898. Serial No. 688,814. Term of patent 14 years.

To all whom it may concern:

Be it known that I, LOUISE A. PITTS, a citizen of the United States of America, residing in the city of Oakland, in the county of Alameda and State of California, have invented and produced a new and original Design for a Cake-Turner, of which the following is a specification, reference being had to the accompanying drawings, forming part thereof.

Figure 1 is a perspective view of a cake-turner. Fig. 2 is a side view, and Fig. 3 a top view, of the utensil.

As shown in the accompanying drawings, the leading or material feature of my design consists of a body A, having an oval outline, a handle B, joining or united to one end in line with the longer axis or side of the oval and standing at an obtuse angle with relation to the body A. This last-named part is flat

on both faces and is divided into several wide 20 prongs or tines *a a* by a number of wide slits *x x*, extending from the end opposite the handle inwardly and lengthwise of the oval. The two outside tines are of less length than the intermediate ones, and the ends of all the 25 tines are tapered to a point. The slits or spaces between the tines exceed in width the breadth of the tines.

Having thus described my invention, what I claim as new, and desire to secure by Letters 30 Patent, is—

The design for a cake-turner as herein shown and described.

LOUISE A. PITTS.
